UNITED STATES PATENT OFFICE.

GEORGE LISTMANN, OF BALTIMORE, MARYLAND.

COAT.

SPECIFICATION forming part of Letters Patent No. 592,149, dated October 19, 1897.

Application filed April 13, 1897. Serial No. 631,897. (No model.)

To all whom it may concern:

Be it known that I, GEORGE LISTMANN, a citizen of the United States, residing in the city of Baltimore, State of Maryland, have invented 5 a new and useful Improvement in Coats, of which the following is a specification.

My invention relates to improvements in coats; and it consists of the novel construction and arrangement of parts hereinafter 10 described and claimed, whereby the skirt thereof may be readily attached or detached, as desired, from the waist thereof.

Figure 1 represents a perspective view of a coat embodying my invention. Fig. 2 represents a sectional view on line $x-x$, Fig. 1. Fig. 3 represents the same parts shown in Fig. 2 separated from each other, so as to more clearly show the same.

Referring to the drawings, A designates 20 the waist part, B the skirts, and C the cape, of the coat, each of said parts being detachable from each other.

The waist A is provided with a series of buttonholes F in its outer face, and on the flap 25 E, which is secured to the lining of the said waist, are attached the buttons or other fastenings D. The upper portion of the skirt B is formed with a pocket G, and in the inner wall of said pocket is a series of buttonholes 30 H, while on the inner face of the opposite wall J of said pocket is a series of buttons K.

In order to fasten the skirt to the waist, the lower end of the waist is inserted in the pocket 35 of the skirt, and the buttons K of the outer wall thereof are engaged in the buttonholes F of the waist, and the buttons D on the flap E are secured in the buttonholes H of the inner wall of the pocket G, the said flap E lapping over and covering the upper edge of 40 said inner wall.

The buttons or fastenings of the two series

are so arranged as not to be opposite each other, whereby an undue thickening or bulging of the parts is prevented.

To cover the seam formed by the top of the 45 outer wall of the pocket of the skirt and the waist a belt L is employed, the said belt passing through loops on said skirt, and extending above the top of said wall of the pocket, its ends being joined in front in any suitable 50 manner.

As will be observed, the skirt thus connected is readily, when desired, detachable from the waist, while at the same time it is reliably held in place on said waist.

Having thus described my invention, what I desire to secure by Letters Patent and claim is—

1. A garment having a waist provided with a flap on its inner face, a skirt having a 60 pocket to receive the lower end of said waist, fastening means connecting said flap and waist with the inner and outer walls respectively of said pocket and a belt covering the 65 seam formed by the top of the skirt and the waist, said belt being suitably held in place on said skirt.

2. A garment having a waist provided with a flap on its inner face above and near the lower edge thereof and extending around the 70 same, a skirt having a pocket at its upper end to receive the lower end of said waist, fastening means for securing said flap to the inner wall of said pocket and fastening means for securing the lower end of said waist to the outer wall of said pocket, the respective fastening means for said flap and lower end of 75 waist being staggered.

GEORGE LISTMANN.
